UNITED STATES PATENT OFFICE

117,114

DESIGN FOR AN INSECT TRAP OR SIMILAR ARTICLE

Thomas J. Williams, Chicago, Ill.

Application July 27, 1939, Serial No. 86,266

Term of patent 14 years

To all whom it may concern:

Be it known that I, Thomas J. Williams, a citizen of the United States and a resident of the city of Chicago, in the county of Cook and State of Illinois, have invented a new, original, and ornamental Design for an Insect Trap or Similar Article, of which the following is a specification, reference being had to the accompanying drawing, forming a part thereof.

On the drawing:

Figure 1 is a side elevation of the insect trap embodying my new design; and
Figure 2 is a top plan view thereof.

I claim:

The ornamental design for an insect trap or similar article, as shown.

THOMAS J. WILLIAMS.
